WALL MOUNTING

Clyde D. Lowry, Toledo, Ohio, assignor to Libbey-Owens-Ford Glass Company, Toledo, Ohio, a corporation of Ohio

Application February 12, 1940, Serial No. 318,436

7 Claims. (Cl. 72—19)

The present invention relates to wall constructions in general and more particularly to the facing of walls with panels or slabs, preferably of structural glass, although the invention is not restricted to the use of panels or slabs of any particular material.

Panels of opaque structural glass are now being widely used for the exterior facing of buildings and store fronts as well as on walls in interior construction. These glass panels are usually of various colors to form an ornamental and pleasing effect. The method of installation commonly practiced consists in simply securing the panels to the supporting wall by means of an asphaltic mastic cement or other suitable cementitious material. This method of attachment has not, however, proven entirely satisfactory in all instances, due to the fact that the glass panels have become separated from the surface to which they are cemented. This may be caused by some procedure of construction or installation being improperly carried out or due to the difference in the coefficient of expansion and contraction of the panels and the surface to which they are secured. The provision of metal structures for mounting glass panels is also known, but in many cases the use of such metal structures requires the beveling or grooving of the edges of the panels or the drilling of holes in the glass to permit the attachment thereof to the metal structure. This special preparation of the glass panels not only renders the mounting of them more costly but, in addition, usually requires more time and also tedious work in the securing of the panels in place.

The primary object of this invention is the provision of an improved metal structure for mounting glass slabs or panels or similar surface covering elements to the exterior and interior walls of building constructions.

Another object of the invention is the provision of an improved metal structure for securing the glass slabs or panels in place without the necessity of grooving, beveling, or otherwise preparing the edges thereof and also without the necessity of drilling holes in the glass for the reception of fastening means.

A further object of the invention is the provision of an improved metal structure for mounting the glass slabs or panels in such a manner that they are yieldably yet securely held in place and at the same time permitted to expand and contract independently of the surface to which they are attached.

A still further object of the invention is the pro-

vision of an improved metal structure to which the glass slabs or panels may be easily and quickly attached and detached so that a broken slab or panel may be readily and conveniently replaced and also whereby the color of the slabs or panels as well as the design thereof may be changed whenever desired.

Other objects and advantages of the invention will become more apparent during the course of the following description, when taken in connection with the accompanying drawings.

In the drawings, wherein like numerals are employed to designate like parts throughout the same:

15 Fig. 1 is a front view of a portion of a wall faced with slabs or panels mounted in accordance with the present invention;

20 Fig. 2 is a vertical perspective sectional view through the metal mounting taken substantially on line 2—2 of Fig. 1;

Fig. 3 is an enlarged detail section of a portion of the metal mounting;

Fig. 4 is a vertical transverse section showing a modified type of metal mounting;

25 Fig. 5 is a horizontal section taken substantially on line 5—5 of Fig. 4; and

Fig. 6 is an enlarged detail section of a portion of the metal mounting.

With reference particularly to Figs. 1, 2, and 3, the numeral 10 designates a supporting wall which may be the exterior or interior wall of a building and to which it is desired to secure the facing slabs or panels 11. The slabs or panels 11 are arranged in a plurality of horizontal and vertical rows and are attached to the wall 10 by means of a plurality of longitudinally extending metal purlins 12. One of these metal purlins is arranged between adjacent horizontal rows of panels and is adapted to engage the upper and lower marginal edge portions of the said panels. Although the slabs or panels 11 will be herein referred to as being of structural glass, it will be understood that they may be of any other desired material.

45 Each purlin 12 comprises a fixed supporting member 13 in the form of a longitudinally extending channel rail comprising spaced upper and lower horizontal portions 14 and 15 respectively connected at their outer ends by an integral vertical web portion 16. The upper horizontal portion 14 of the channel rail is provided at its rear end with a vertically directed attaching flange 17 adapted to be secured to the wall 10 by suitable fastening means such as screws or

50 the like 18. Also formed integral with the up-

per horizontal portion 14 of the channel rail is an upwardly projecting longitudinally extending rib 19, while formed integral with the attaching flange 17 is a forwardly and downwardly projecting longitudinally extending rib 20; said ribs 19 and 20 cooperating with one another to form therebetween an undercut channel 21 adapted to receive a strip of cushioning material 22 preferably of rubber, rubber composition, or other suitable resilient, compressible material. The cushioning strip 22 is provided with a key portion 23 received within the channel 21 and with an outer portion 24 adapted to engage the rear faces of the slabs or panels 11 which are disposed above the channel rail 13.

The lower horizontal portion 15 of channel rail 13 is provided at its rear end with a downturned longitudinally extending flange 25 formed at its lower end with a forwardly and upwardly directed rib 26. Formed integral with the lower horizontal portion 15 of the channel rail is a longitudinally extending depending rib 27 cooperating with rib 26 to form therebetween an undercut channel 28 for receiving the cushioning strip 29. The cushioning strip 29 is similar to cushioning strip 22 and is adapted to engage the rear faces of the slabs or panels 11 disposed beneath the channel rail 13. In other words, the cushioning strips 22 engage the panels of one course adjacent their lower ends, while the cushioning strips 29 engage the panels of the next lower course adjacent their upper ends.

Carried by the channel rail 13 is a forwardly directed T-member comprising a horizontal stem 30 integral with the web 16 of the channel rail intermediate the upper and lower ends thereof and provided at its outer end with a substantially vertical face member 31, the outer surface of which may have any desired cross sectional contour. Formed integral with the channel rail 13 are the forwardly directed longitudinally extending shoulders 32 and 33 which cooperate with the stem 30 of the T-member to form longitudinally extending grooves 34 and 35.

Associated with the channel rail 13 and T-member carried thereby are wing members 36 and 37 which are adapted to engage the outer faces of the slabs or panels 11 to hold them securely in place. Each wing member comprises a face portion 38 provided at its outer end with a bead 39 engaging the front faces of the respective slabs or panels. The face portion 38 is provided at its inner end with a rearwardly offset attaching portion 40 resulting in a shoulder 41 adapted to engage the longitudinal edge of the face member 31 of the T-member and which edge constitutes a fulcrum upon which the wing member is adapted to rock or pivot. The rearwardly offset attaching portion 40 is received behind the vertical face piece 31 and is formed at its free end with a laterally directed toe 42 received within the respective groove 34 or 35. When the wing member is caused to pivot or fulcrum outwardly upon the face piece 31, the toe 42 is swung inwardly to engage the respective shoulder 32 or 33 as indicated at 43 (Fig. 3).

When installing the slabs or panels 11, the wing members 36 and 37 are first removed. The panels of one row are then supported on edge upon the channel rail 13, with their rear faces in engagement with cushioning strip 22. The operator then forces the panels rearwardly to compress the strip 22 and while held in this position the wing member 36 is slipped into place, with the shoulder 41 thereof engaging the upper edge

of the face member 31 and the toe 42 received within groove 34. The panels are then released and the resiliency of the cushioning strip 22 will force them forwardly thereby causing the wing member 36 to fulcrum or rock upon the face member 31 until the toe 42 engages the shoulder 32 as indicated at 43 in Fig. 3. When this is done, the panels will be securely, yet yieldably, held in place so that they are free to expand or contract independently of the supporting metal structure as well as independently of the wall 10. The row of panels beneath the channel rail are then installed in the same manner and yieldably clamped between the cushioning strip 29 and wing member 31. When it is desired to replace a broken panel or change the color or design of the panels, it is simply necessary to force the panels rearwardly to compress the cushioning strip 22 or 29 sufficiently to permit the removal of the desired wing member. The row of panels above the channel rail 13 is supported thereupon and preferably rests upon a strip 44 of suitable cushioning material such as felt, cork, or the like. The vertical spaces between horizontally adjacent blocks may be filled with a suitable pointing or caulking material as indicated at 45 (Fig. 1).

In Figs. 4, 5, and 6 is illustrated another type of metal mounting also embodying the principles of the present invention. As herein shown, the rear supporting wall is also designated by the numeral 10, the facing slabs or panels by the numeral 11, and the longitudinally extending purlins by the numeral 12. In this form of the invention, however, the purlins 12 are of a somewhat different construction. Each purlin comprises a fixed member 46 comprising a longitudinally extending channel rail including the upper and lower horizontal portions 47 and 48 connected at their outer ends by the integral vertical web 49. Formed integral with the upper horizontal portion 47 of channel rail 46 is an upstanding flange 50, over the upper edge of which is fitted a cushioning strip 51 of rubber, rubber composition, or the like, engaging the rear faces of the respective row of slabs or panels. Formed integral with the lower horizontal portion 48 of the channel rail is a depending flange 52 also carrying a cushioning strip 53 engaging the rear faces of the next lower row of slabs or panels. The lower horizontal portion 48 of the channel rail extends rearwardly beyond the flange 52 as indicated at 54 and is adapted to engage the wall 10 to properly space the channel rail therefrom. Formed integral with the upper horizontal portion 47 of the channel rail is a depending rib 55 having associated therewith a plurality of hangers 56. Each hanger 56 comprises a vertical attaching portion 57 secured to the back wall 10 by screws or the like 58. Formed at the lower end of the attaching portion 57 is a forwardly offset substantially U-shaped supporting portion 59 having a groove 60 for receiving the flange 55 therein. Any desired number of these hangers may be associated with the channel rail 46, and preferably consist of relatively short sections as best shown in Fig. 5.

The channel rail 46 is provided with the forwardly projecting longitudinally extending shoulders 61 and 62 which cooperate with the vertical web portion 49 to provide a channel 63. Passing loosely through openings in the web portion 49 are a plurality of horizontal bolts 64 provided at their forward ends with heads 65 received within a longitudinally extending channel 66 formed

in the back of the face member 67 which may have any desired profile. The face member 67 is normally drawn inwardly by means of a plurality of leaf-springs 68 of bow formation, one being slidably received upon each of the bolts 64 and held thereon by a nut 69.

Associated with the face member 67 are the two wing members 70 and 71 similar to those illustrated in Figs. 2 and 3 and associated with the face member in substantially the same manner. Thus, each wing member comprises a face portion 72 provided at its outer end with a bead 73 engaging the front faces of the respective row of slabs or panels 11. The face portion 72 is provided along its inner end with a shoulder 74 engaging the adjacent edge of the face member 67 and with a rearwardly offset attaching portion 75 terminating in a toe 76 which is received within the channel 63 and adapted to engage the respective shoulder 61 or 62 as indicated at 77 (Fig. 6).

In the operation of this type of mounting, the leaf-springs 68 are normally arcuately bowed as shown in full lines in Fig. 5 so that they tend to draw the face member 67 inwardly to hold the outer ends of the wing members 70 and 71 in yieldable engagement with the front faces of the slabs or panels and the rear faces of the slabs or panels against the cushioning strips 51 and 53. However, when it is desired to remove any one of the panels, the operator, by means of a suitable tool, forces the face member 67 forwardly, whereupon the springs 68 will be caused to flatten out as indicated by the broken lines. While the face member 67 is held in forward position, the wing members can be removed to permit removal of the desired panel or panels. In this type of mounting the row of slabs or panels above each purlin 12 is supported upon the channel rail 46 and a cushioning strip 78 may be provided between the glass and metal to minimize breakage of the former.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and supporting the upper row of panels thereupon, means carried by said fixed member and engaging the rear faces of the panels in the adjacent rows, a longitudinally extending face member carried by said fixed member and disposed forwardly of said panels, and wing members arranged at opposite sides of said face member and engaging the front faces of the panels in said adjacent rows, said wing members having attaching portions received behind said face member and engaging the said fixed member and other portions engaging the said face member for rocking movement thereon.

2. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and sup-

porting the upper row of panels thereupon, cushioning means carried by said fixed member and yieldably engaging the rear faces of the panels in the adjacent rows, a longitudinally extending face member carried by said fixed member and disposed forwardly of said panels, and wing members carried by said face member and engaging the front faces of the panels in said adjacent rows, said wing members having attaching portions disposed behind the said face member and engaging the said fixed member and other portions engaging the said face member for rocking movement thereon.

3. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and supporting the upper row of panels thereupon, means carried by said fixed member and engaging the rear faces of the panels in the adjacent rows, a longitudinally extending face member carried by said fixed member and disposed forwardly of said panels, and wing members carried at opposite sides of said face member for rocking movement thereon to engage the front faces of the panels in said adjacent rows, said fixed member having forwardly projecting longitudinally extending shoulders and said wing members having attaching portions disposed behind said face member and provided with toes engaging the shoulders on said fixed member upon rocking of the said wing members on the said face member.

4. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and supporting the upper row of panels thereupon, strips of cushioning material carried by said fixed member and engaging the rear faces of the panels in the adjacent rows, a longitudinally extending face member carried by said fixed member and disposed forwardly of said panels, and wing members carried at opposite sides of said face member for rocking movement thereon to engage the front faces of the panels in said adjacent rows, said fixed member having forwardly projecting longitudinally extending shoulders and said wing members having attaching portions disposed behind said face member and provided with toes engaging the shoulders on said fixed member upon rocking of the said wing members on the said face member.

5. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and supporting the upper row of panels thereupon, means carried by said fixed member and engaging the rear faces of the panels in the adjacent rows, fastening elements passing loosely through openings in said fixed member, a longitudinally extending face member carried by said fastening elements and disposed forwardly of said panels, wing members rockably carried by said face member and engaging the front faces of the panels in said adjacent rows, spring members

carried by said fastening elements rearwardly of said fixed member acting to normally draw said face member inwardly, and cooperative means on the wing members and fixed member for keeping them assembled and for maintaining said wing members in yieldable engagement with the said panels.

6. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and supporting the upper row of panels thereupon, a forwardly directed T-member carried by said fixed member and comprising a horizontal stem integral with the said fixed member intermediate the upper and lower ends thereof and provided at its outer end with a substantially vertical face member, said fixed member being also provided with forwardly directed longitudinally extending shoulders cooperating with the stem of said T-member to form longitudinally extending grooves, wing members detachably associated with said vertical face member and provided at their inner ends with rearwardly offset attaching portions resulting in shoulders engaging the respective longitudinal edges of said face member and upon which said wing members fulcrum, the outer ends of said wing members engaging the facing panels while the rearwardly offset attaching portions thereof are received behind said vertical face member and provided with laterally directed toes received within said longitudinal grooves, and means carried by said fixed member and positioned rearwardly of said facing panels to yieldably hold said panels outwardly against said wing mem-

bers and rock said wing members upon said face member to maintain the toes thereof within the longitudinal grooves in said fixed member.

7. The combination with a supporting wall and facing panels therefor arranged in a plurality of rows, of longitudinally extending horizontal metal purlins for attaching said panels to said wall, each comprising a fixed member secured to said wall and extending longitudinally between two vertically adjacent rows of panels and supporting the upper row of panels thereupon, a plurality of bolts passing loosely through openings in said fixed member and carrying nuts at their inner ends, a face member carried at the forward ends of said bolts, the said fixed member being provided with forwardly projecting longitudinally extending shoulders cooperating with said fixed member to form a channel, wing members detachably associated with said face member and provided at their inner ends with rearwardly offset attaching portions resulting in shoulders engaging the respective longitudinal edges of said face member and upon which said wing members fulcrum, the outer ends of said wing members engaging the facing panels while the rearwardly offset attaching portions thereof are received behind said vertical face member and provided with laterally directed toes which are received within said channel and engage the respective shoulders on said fixed member, oppositely directed flanges carried by said fixed member and engaging the rear surfaces of said panels, and spring members carried by said bolts between the nuts thereon and said fixed member and acting to normally draw said face member inwardly to hold the outer ends of the wing members in yieldable engagement with the front surfaces of said facing panels.

CLYDE D. LOWRY.
